UNITED STATES PATENT OFFICE.

MARY G. HATCH, OF NEW YORK, ASSIGNOR TO M. H. BIRGE & SONS, OF BUFFALO, NEW YORK.

DESIGN FOR WALL-PAPER.

SPECIFICATION forming part of Design No. 22,943, dated November 28, 1893.

Application filed October 21, 1893. Serial No. 488,822. Term of patent 3½ years.

To all whom it may concern:

Be it known that I, MARY G. HATCH, a citizen of the United States, residing at New York, in the county and State of New York, **5** have invented and produced a new and original Design for Wall-Paper, of which the following is a specification.

The design consists of an arrangement of flowers and leaves of the "iris" in vertical **10** rows or lines upon a striped background, with the leaves of each row interlacing or crossing the leaves of the adjacent rows as represented in the accompanying drawing.

The stripes forming the background of the

design terminate at their tops in Gothic style **15** of ornaments, and small fleur-de-lis shaped ornaments are arranged in rows above the stripes and vertical rows of flowers and leaves as shown.

What I claim is—

The design for wall paper herein shown and described.

Witness my hand this 14th day of October, 1893.

MARY G. HATCH.
